Primary Examiner — Jennifer Rivard

(57) **CLAIM**

I claim the ornamental design for a combined photon hair removal instrument and stand, as shown and described.

DESCRIPTION

FIG. 1 is a perspective view of a combined photon hair removal instrument and stand showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof.

The broken lines illustrate portions of the combined photon hair removal instrument and stand that form no part of the claimed design.
